UNITED STATES PATENT OFFICE

2,465,603

PARTITION

Joseph A. Potchen, Grand Rapids, Mich., assignor
to Haskelite Manufacturing Corporation,
Grand Rapids, Mich., a corporation of New
York

Application April 9, 1947, Serial No. 740,293

7 Claims. (Cl. 20—4)

1

The invention relates to wall or partition construction of the type which includes laminated panels.

In wall or partition constructions, it has been found advantageous to use panels which include bonded inner laminations or plies, of wood veneer, and outer laminations of metal adhesively bonded to the veneer, for high strength-weight ratio. In walls or partitions embodying panels of this type, it is desirable to provide constructions which can be easily fabricated, and readily assembled with bars of metal. It is also desirable to provide joints between the panels and the bars which will withstand torsional stresses, and will avoid crazing and breaking of the panels while in service.

One object of the invention is to provide a wall or partition construction with panels of metal and veneer laminations which are adapted to be readily assembled between bars or columns, and which when assembled, will form a wall or partition which in service, will not craze or become distorted, and has a high strength-weight ratio.

Another object of the invention is to provide a method of assembling a wall or partition construction with the aforesaid laminated panels which can be inexpensively fabricated and easily installed.

Other objects of the invention will appear from the detailed description.

The invention consists in the several novel features hereinafter set forth, and more particularly defined by claims at the conclusion hereof.

In the drawings:

Fig. 1 is a perspective of a portion of a wall or partition embodying the invention.

Fig. 2 is a section on an enlarged scale, of a portion of a panel of laminated stock used in fabricating the panels.

Fig. 3 is a similar section illustrating the groove formed in the edges of the panels to provide bendable portions along the edge of the panel.

Fig. 4 is a similar section illustrating the panel after the bendable portions at the sides of the groove, have been shaped to form a cross-sectionally tapered margin, for fitting into the channel in a bar.

Fig. 5 is a similar section showing the tape applied to the margin of the panel.

Fig. 6 is a similar section illustrating a bar and the contiguous tapered marginal portions of a pair of panels secured in the channels in a bar.

Fig. 7 is a section illustrating a corner con-

2

struction for walls or partitions extending at right angles to each other.

The invention is exemplified in Fig. 1, in a wall or partition which comprises panels generally designated 15, and bars 16 joining the contiguous edges of the panels. The bars may be of the extruded type and are usually formed of light-weight metal such as aluminum or its alloys.

Each panel comprises inner laminations or plies of wood veneer in the desired number, the grain of the alternate laminations 20, 21, extending crosswise or angularly of another, and outer laminations of metal 22, all of which are bonded together with suitable thermo-setting adhesives, as well understood in the art. The panels are usually rectangular in contour. The panels, after the laminations are bonded together, are first cut with straight right-angled longitudinal edges 23, as illustrated in Fig. 2. Next, a straight-sided longitudinal groove 24 is cut into each edge of the panel which is to be secured in a bar 16, as illustrated in Fig. 3. The groove 24 is of such width as to leave portions 25 of veneer and the metal laminations 22 at both sides of the groove 24. Next, the portions of the panel at the sides of the groove are bent together, as indicated at 26 in Fig. 4, to form a cross-sectionally tapered longitudinal margin along each grooved edge of the panel. In this bending operation, as shown in Fig. 4, the metal laminations 22 are angularly bent as at 27, and portions 25 of veneer will be bent angularly as at 28. In this bending operation, the contiguous corners of the portions 26 of veneer, are preferably brought together and the groove 24 will be deformed to substantially triangular cross-sectional contour. The oppositely disposed edges of the panels are both cut and shaped in this manner, when both are to be joined to bars 16.

Each bar 16 has longitudinal channels 30 of flared cross-section conforming approximately to the cross-sectional taper of the margin of the panel. Before joining the panels and the bars, each tapered margin and longitudinal edge of the panel is lined with suitable adhesive tape 31, as shown in Fig. 5.

In assembling a wall or partition, the tapered longitudinal edges of the panels are inserted into the flared channels 30 of the bars 16 and the panels and bars are forced together in wedging relation. The tape 31 eliminates any crazing which might result from metal-to-metal contact between the metal laminations of the panels and the bars. The faces of the panels when they have been joined to the bars, are

flush with the outer faces of the bars. When the panels and bars have been assembled and joined together as illustrated in Fig. 6, it has been found by test, that torsional and other stresses to which the wall or partition may be subjected, do not damage the panels or the joints, and do not cause crazing. In practice, these panels and bars may be supported at their upper and lower ends by fixed beams, and it has been found in practice that the joints between the bars and the panels adequately support the wall or partition between the beams.

The tapered portions at the sides of the grooves are resilient and when forced into the channels in the bars, become wedged against the flared sides of the channels in the bars, to form an efficient and tight-fitting joint. When the contiguous corners of the veneer at the longitudinal edge of the panel are in contact, the compressibility and resiliency of the veneer aid in making the joint secure.

In the modification illustrated in Fig. 7, a T-shaped panel 35 is used to form corners between partitions or walls at right angles to each other. This T-shaped panel comprises straight inner laminations of wood veneer 36 and an outer straight lamination 37 of metal bonded thereto, angularly bent corner laminations of wood veneer 38 with outer laminations 39 of metal bonded thereto. The three longitudinal margins of the panel 38, are grooved and bent in the same manner as previously described and each is adapted to be joined to a bar 16 having a flared channel for receiving the panel, in the manner previously described.

The invention is not to be understood as limited to the details described, since these may be modified within the scope of the appended claims without departing from the spirit or scope of the invention.

Having thus described the invention, what I claim as new and desire to secure by Letters Patent is:

1. A composite wall construction, comprising: a panel including interior laminations of wood veneer and outer laminations of metal adhesively bonded together, at least one edge of the panel having its central portion cut away so as to leave some veneer and the lamination of metal at each side of the groove, the remaining portions of the laminations at the sides of the groove being bent to form a cross-sectionally tapered margin, and a bar having a flared channel with sides between which the tapered margin is wedgingly confined.

2. A composite wall construction, comprising: a panel including interior laminations of wood veneer and outer laminations of metal adhesively bonded together, at least one edge of the panel having its central portion cut away so as to leave some veneer and the lamination of metal at each side of the groove, the remaining portions of the laminations at the sides of the groove being bent to form a cross-sectionally tapered margin with the contiguous corners of the veneer substantially in contact along the longitudinal edge of the panel, and a bar having a flared channel with correspondingly tapered sides between which the tapered margin is wedgingly confined.

3. A composite wall construction, comprising: a panel including interior laminations of wood veneer and outer laminations of metal adhesively bonded together, at least one edge of the panel

having its central portion cut away so as to leave some veneer and the lamination of metal at each side of the groove, the remaining portions of the laminations at the sides of the groove being bent to form a resilient cross-sectionally tapered margin, and a bar having a flared channel with sides between which the tapered margin is wedgingly confined.

4. A composite wall construction, comprising: 10 panels each including interior laminations of wood veneer and outer laminations of metal adhesively bonded together and having oppositely disposed longitudinal edges with the central portions of the veneer being cut away longitudinally at said edges so as to leave some veneer and the lamination of metal at the sides of the cut-aways, the remaining portions at the sides of the cut-aways being bent to form cross-sectionally tapered longitudinal margins, and bars having 15 flared channels therein with sides between which the tapered margins of the panels are wedgingly confined.

5. A composite wall construction, comprising: 20 panels each including interior laminations of wood veneer and outer laminations of metal adhesively bonded together and having oppositely disposed longitudinal edges with the central portions of the veneer being cut away longitudinally at said edges so as to leave some veneer and the lamination of metal at the sides of the cut-aways, the remaining portions at the sides of the cut-aways being bent to form cross-sectionally tapered longitudinal margins with contiguous corners in contact at the edges of the panels, and 25 bars having flared channels therein with sides between which the tapered margins of the panels are wedgingly confined.

6. That improvement in constructing walls which include panels having interior laminations 40 of wood veneer and outer laminations of metal and bars having cross-sectionally flared channels for the edges of the panels which comprises: cutting longitudinal grooves in the edges of the panels so as to leave some of the veneer and the lamination of metal at each side of the groove, bending the portions at the sides of the groove to form cross-sectionally tapered longitudinal margins and assembling the panels and the bars with the tapered margins of the panels in the flared 45 channels in the bars.

7. That improvement in constructing walls which include panels having interior laminations of wood veneer and outer laminations of metal and bars having cross-sectionally flared channels 50 for the edges of the panels which comprises: cutting grooves in the edges of the panels so as to leave some veneer and the lamination of metal at each side of the groove, bending the portions at the sides of the groove to form cross-sectionally tapered longitudinal margins and assembling the panels, inserting tape between the bars and tapered margins of the panels.
